BUILDING MATERIAL AND THE LIKE

Norman P. Harshberger, Scarsdale, N. Y., assignor to Bakelite Building Products Co. Inc., New York, N. Y., a corporation of Delaware

Original application June 22, 1935, Serial No. 27,989, which is a division of application Serial No. 484,079, September 24, 1930. Divided and this application April 17, 1937, Serial No. 137,401.

9 Claims. (Cl. 108—8)

This invention relates to roofing and siding elements, to surface coverings thereof, and to methods of making such material, and is a division of my co-pending application Serial No. 27,989, filed June 22, 1935, which, in turn, is a division of my Patent No. 2,006,270, granted June 25, 1935, upon an application filed September 24, 1930, bearing Serial No. 484,079. More particularly, the invention is directed to a composite structure comprising waterproof covering material and a porous or cellular sheet-like heat and cold insulating layer whereby to obtain a product and surface covering of especially high insulation value. The invention further contemplates a novel interlock and emphasized shingle and butt effects.

It is one of the objects of the invention to provide improved roofing and siding elements, including a facing manufactured from the usual composition material, for instance, a waterproofed fibrous base having a granular surfacing, for instance, of slate or similar materials held to the base by a suitable adhesive binder.

It is a further object of this invention to provide roofing and siding elements which are formed and cut in a novel manner so as to be capable of simulating a plurality of figures when applied to building and having emphasized butt effects.

A further object of the invention is to provide improved roofing and siding elements of composite structure to furnish maximum protection in weather exposure.

An additional object of the invention is to provide composition building material utilizing a plurality of thicknesses to obtain unusual rigidity at the exposed portions of the material and effectively withstand action of the weather thereon.

A more specific object of the invention is to provide roofing and siding elements of high insulating character through the provision of a strata of fibrous or mineral material, for instance, cork, having especially high insulating characteristics.

A more specific object is to provide a composite element of high insulation value which comprises an insulating layer, for instance, cork, in the form of a filler piece between layers of composition roofing.

Another object of the invention is the provision of roofing elements having a mortise at one end and a tenon at the other, which elements may be assembled in courses to form a continuous cov-

ering and creating mortise and tenon joints between the adjacent elements in a course.

A further object of the invention is to provide a siding covering simulating clapboard siding wherein the elements constitute a composite structure comprising an insulating board layer and a sheet of waterproof composition material.

With the above and other objects in view, the invention consists in the improved roofing and siding elements, the manner of assembly and covering made thereof, the method of manufacture, and all parts and combinations thereof, as set forth in the claims and all equivalents thereof.

In the accompanying drawings, in which the same reference numerals indicate similar parts—

Fig. 1 is a plan view of an element comprising an insulating layer and a facing layer;

Fig. 2 is a sectional view taken on line 2—2 of Fig. 1, and

Fig. 3 is a fragmentary perspective view illustrating a method of interconnecting the ends of adjacent elements of Fig. 1.

Fig. 4 is a plan view of an assembly of elements of Fig. 1.

Referring to the figures of the drawings, it will be seen that the element herein illustrated comprises a body or weather sheathing 2, which may be a layer of flexible waterproof roofing material surfaced with a layer of adhesive, for instance, asphalt, and having crushed mineral material embedded therein. Adjacent the body layer is a layer 6 of insulating material, which may be of cork, or may be of any fibrous or mineral material which will improve the insulating qualities of the element. This layer preferably constitutes a self-sustaining sheet-like layer having physical properties preferably including stiffness, enabling its efficient use as a tenon member in the manner disclosed in Fig. 3 of the drawings. As disclosed in the drawings, the layer 6 is preferably of greater thickness than the body layer 2 and provides substantial insulating properties, as well as rigidity for the product of which it forms a part. These proportions can be obtained without excessive weight because of the lower density of the insulating layer 6.

In the preferred form of structure, it will be noted that the body portion 2 is formed with a fold at the lower edge in which to receive the insulating layer 6. In this manner the lower edge of the layer 6 may, if desired, be fully covered and protected from the weather. It will be understood that the upper edge of the layer 6 when

uncovered will be covered by the next overlying element in assembly. Moreover, according to this mode of construction, any surface ornamentation on the layer 2, may be carried around the 5 butt edge of the layer 6. It will be further understood that in manufacture, the body 2 may be folded upon the layer 6, or the body 2 may be prefolded ready to receive the layer 6.

It will be observed from the drawings that the 10 body layer 2, preferably forms a continuous layer covering two sides and an edge of the layer 6, in effect, creating a sandwich-type structure. It will be appreciated that a structure of this character will have additional rigidity by reason of 15 the multiple layer composite construction and that the layer 6 will be protected on both faces. More particularly, it will be understood that either side of the product may be exposed to the weather. Various visual and color effects may 20 thus be produced and the elements in the courses may be laid in either direction starting from the left or right.

Figs. 1 and 3 show the body layer on one side of the insulation layer 6 divided into a plurality of 25 sections 4, preferably integrally connected to the opposite body portion and creating, in effect, shingle-like exposures with a depressed joint between them. The body portion of such a structure may readily be formed from a web of material severed at one edge to create a plurality of 30 tabs similar in character to 4, and the tabs 4 may be folded about the layer 6 in a manner as to cause the upper end of the recesses between tabs to be substantially flush with the lower 35 edge of the layer 6 so that the fold may be made uniformly and without buckling the rear side of the body 2 and to substantially hide from view any cut edges of the body material if they be not sealed.

40 It is preferred that the body layer 2, especially the sections 4, where such are formed, be secured to the layer 6, for instance, by cementing or otherwise. Such, however, is not essential where the parts are held together by the securing means 45 fastening the composite elements to a surface. In certain cases where expansion of the layers 2 and 6 might be conducive of buckling if fastened together, it is preferred that the parts be free.

A feature of the invention relates to a composite structure of the above character, which 50 may be readily assembled. It will be observed from Figs. 1 and 3 that the layer 6 may extend longitudinally beyond one end of the body 2 to form a projection 8 and may be spaced inwardly 55 longitudinally at the opposite end of the body 2 so as to provide a recess 10 between the folded portions of the body layer. It will be readily evident from Fig. 3, that elements embodying these features may be assembled end to end, the projection 8 nesting in the space or recess 10 of an adjacent element and thereby forming an 60 interlocking engagement of mortise and tenon character. It will be understood that the length of the projection 8 and the depth of the recess 10 will be determined by the portion of the body 2 to be exposed and necessities of the joint. Where 65 sections 4 are to be exposed, it may be desired to continue the formation of the depressed spaces between the portions 4 of adjacent elements, and the projection 8 may then be of a length at least 70 equivalent to the longitudinal depth of the recess 10, plus the width of the space between two sections 4, the end of the layer 6 in the recess portion of the body acting as a registering stop 75 for the opposite end of that layer. It will be

understood, however, that the separation may be obtained without causing the ends of adjacent layers 6 to abut. When the opposite face of the body 2 is to be exposed or the structure does not include the configuration 4, such spacing may be dispensed with and the projection 8 need only be of sufficient length to form an efficient interlock. The ends of the adjacent body portions 2 may be abutted or spaced slightly to allow for expansion.

The elements may be assembled in courses, for example, in a manner disclosed in Fig. 4, exposing the sections 4, or they may be assembled in a similar manner with the opposite side of the body 2 forming the exposed facing. Obviously, the adjacent elements in a course will be preferably assembled and interlocked by means of the mortise and tenon joint, which is a feature of the present invention. In this manner, an interlock is obtained and the surface and edge effect at the joint is not marred. Also the mortise end of the element serves to support the tenon end. When lap joints are employed, as will be evident from Fig. 15 of my prior Patent No. 2,006,270, no interlock is obtained and the surface and edge effect is marred by the lapping portions. Also no support is provided and both layers must be fastened, as by nails.

It will also be evident that the rigidity of my elements promotes easy handling prior to and during assembly, and makes assembly of adjacent elements and courses thereof a simple matter. When assembled in the manner indicated, elements of the character here illustrated are adapted to simulate clapboard siding from which an extremely desirable shadow effect will be obtained. Obviously, such a covering will readily resist any tendencies to lift in the wind. Also, by reason of the insulating layer 6, a covering of high insulation character will be obtained.

It will be understood that, in general, it is merely necessary to have the body portion 2 of waterproof character. Where sections 4 are to be exposed, it is preferred that the layer 6 also be of waterproof character or have that portion exposed in the depressions formed between the sections 4 protected. This may be readily accomplished by a waterproof coating which may also be the cementing means for the sections 4. The exposed portions 4 may also be treated in any of the ways disclosed in my prior Patent No. 2,006,270 to obtain contrasting color effects with the layer 6. It will also be understood that the joining ends of the elements may be treated with cement in assembly should such procedure be desirable.

From the above description, it will be apparent that very novel roofing and siding elements are provided, adapted to provide a heat and cold insulating medium of high character, and provide a surface covering of high weather resistance. Also means are presented to produce the effect of sharply defined configurations and novel means are included for assembling and interlocking the elements. The various layers of body material and insulating material combine to produce an extremely desirable covering. It will be obvious that various modifications and changes may be made by those skilled in the art, for example, in the configurations formed, in the method and extent of folding the body portion about the insulating layer, as well as in the method of assembly, without departing from the disclosed features.

Accordingly, it is desired that the invention be

construed as including all equivalents and as broadly as the claims, when taken with the prior art, may allow.

I claim:

5. A building element comprising a substantially flat member forming a center core, material secured to both faces of said core and integrally connected at one edge of the core by a line of fold, one face of said element presenting a plurality of raised figures separated by intervening transverse spaces, exposing the center core, one end of said core projecting beyond the same end of the covering material to form a tenon, and a second end of said core being spaced back 10 from a second end of said covering material to form a mortise, said element being adapted to form mortise and tenon joints with adjacent elements to form a weather-tight joint to aline the elements and to produce transverse spaces at 15 said joints to form a continuous course of elements presenting a plurality of raised figures separated by intervening spaces.

2. A roofing and siding element comprising a sheathing strip and a filler member, said sheathing strip formed with a fold at the butt edge of the element, and said filler member nesting in said fold, said fold extending beyond the filler at one end of the element to create a mortise closed at the butt edge, and said filler member 20 extending beyond the sheathing at the opposite end of the element to form a tenon to engage the mortise of another element in the same course in assembly.

3. A roofing and siding element comprising a substantially flat core member, sheet covering material extending from a face of said core member about the butt edge thereof and over the opposite face, the cover sheet extending beyond the core at one end to form a mortise closed at the butt edge, and said core extending beyond the cover sheet at the opposite end to form a tenon to engage the mortise of another element in the same course in assembly, said cover sheet on the side of said element to be exposed presenting a plurality of raised configurations separated by narrow transverse depressions setting off said configurations.

4. A roofing and siding element as claimed in claim 3, wherein the configurations are surfaced with material of a contrasting color from that appearing in the depressions.

5. A surface covering of elements as claimed in claim 3, comprising overlapping courses of said elements arranged with the adjacent elements in the courses interlocked by mortise and tenon joints, said elements also having their butt edges in substantial alignment and having narrow spaces formed at the joints between adjacent elements, whereby to present continuous courses of elements presenting a plurality of raised configurations separated by intervening depressions. 10

6. A building element as claimed in claim 1, wherein the portions of the core to be exposed in assembly are surfaced with a water-resistant material. 15

7. A surface covering comprising elements as claimed in claim 3, wherein said elements are arranged in longitudinal courses with their butt edges in substantial alignment and with their mortise and tenon portions treated with a cemen- 20 titious material and interlocked.

8. As an article of manufacture, a roofing and siding element comprising a relatively stiff insulation slab and a weather-resistant sheathing strip abutting the opposite faces of said slab and terminating in a fold at the lower edge thereof, there being a mortise at one end of the element formed by the sheathing material and a tenon formed at the other end of the element by the slab, the said tenon being adapted to engage with 30 the mortise of a similar element in assembly.

9. An insulated surface covering comprising overlapping courses of building material, each course comprising adjacent sections of cellular insulation material lying substantially in the same place and having sheathing strips of weather-resistant material abutting the opposite faces thereof and terminating in a fold at their lower edges; the sheathing strip for each insulating section also extending at one end to form a mortise and the insulating section extending beyond the opposite end of the same strip to form a tenon; the mortise and tenon of adjacent insulation sections and sheathing strips being interlocked and said courses being laid with the sheathing strips in a course extending under the next overlying course of insulation sections and strips to form a continuous weather covering of substantial insulation value. 40 45

NORMAN P. HARSHBERGER. 50
